ATTORNEY.

UNITED STATES PATENT OFFICE.

FRANK R. CARGILL, OF CHICAGO, ILLINOIS.

JOURNAL-BEARING.

SPECIFICATION forming part of Letters Patent No. 280,347, dated July 3, 1883.

Application filed April 17, 1883. (No model.)

To all whom it may concern:

Be it known that I, FRANK R. CARGILL, of Chicago, county of Cook, and State of Illinois, have invented a new and useful Improvement 5 in Journal-Bearings, of which the following is a specification, reference being had to the accompanying drawings, illustrating the improvement, in which—

Figure I is a perspective representation of 10 a half bearing or shell embodying my improvement; Fig. II, a transverse section thereof cutting the strengthening-rib; Fig. III, a central sectional longitudinal elevation of Fig. I.

15 The object of the present invention is to provide a shell journal bearing or box which shall be of suitable strength and retain the soft or anti-friction metal entirely within rims or projections, and at the same time have the 20 soft metal cover the strengthening-rib.

It has formerly been the custom to line journal-bearings with soft or anti-friction metal, and also to run or cast the metal in a matrix made in a simple form in the shell traversed 25 by strengthening-ribs. Various forms are shown in the following patents: The patent to John Sweeney, No. 199,699, shows a box cast round a dovetail rib, with the anti-friction metal cast on the inside of the box and 30 over the rib; but the soft metal comes flush with the ends of the box, and as a result in practice the soft metal will be swaged endwise, forming sharp edges, which will cut the shoulders of the journals. The patent to B. J. 35 Downs, No. 236,560, shows a box more nearly like the one sought to be patented than any of which I have knowledge; but the strengthening-rib comes even with the curved ribs at the ends of the box; and if only the matrices 40 are to be filled with soft metal the central rib will at all times come in contact with the journal. This is a serious objection in the construction of boxes, inasmuch as there are two separations between the hard and soft metal, 45 very near the central main bearing-point of the journal and longitudinally with its axis. The point of objection is, the soft metal is swaged over the rib at any time the box gets hot, unless the bearing is on the rib, in which 50 case the soft metal is of but little use. I obviate these objections by means of a box whose

matrix is about twice the depth at the edges of the rib as at the margins of the box, and employing a rib which projects up from the matrix about one-half of the central depth of 55 the matrix, and then solder the anti-friction metal to the matrix and to the rib, and bringing the said metal flush with the curved ribs at the ends of the shell-box. By this means the holes shown through the shell in Patent No. 60 236,560 are obviated, and the liability of breakage therefrom removed; and at the same time I have a ribbed matrix filled with a single sheet of metal butting against flanges, both at the ends and sides of the box. It is this special construction which I claim to have invented, and ask therefor a patent. It is observed that these boxes are designed to be used for the better class of machinery, and, being in shell form and light, they are made of strong, 70 tough metal, good cast-brass being suitable.

A' represents the shell of one-half of a box, which is formed with two matrices, A, side flanges, D D, end flanges, B B, and a strengthening-rib, S, extending from flange B to B, but 75 is only about one-half so thick as the depth of the matrix at the edges of the rib S. This shell has soft or anti-friction metal soldered in the shell-cavity to fill the same flush with the face of the flanges B, covering the rib S, as 80 shown at Fig. II, by a single sheet of metal.

The especial purpose of inclosing all the box metal proper within the shell is that such used by the applicant is very soft, much more so than the ordinary Babbitt metal, and unless the soft metal be wholly inclosed with ribs at the central faces the action of the journal will draw it out in thin-cut sheets, which, by the action of the oiler, are returned, and cut the box. In this respect my box differs from 90 the journal-bearing patented to De W. C. Clough on June 23, 1874, inasmuch as in his the soft metal comes in full-width sheet to the central face or top of the box, and forms square angles at those places, while the soft metal in 95 my box lies wholly within flanges at the ends and faces thereof. Further than this, the matrices at the edges of the central rib are deeper than at the top of the box. The Clough box is lined with a semi-cylindrical sheet of metal 100 tongued into the sheet, the tongues being some distance from the top.

The depth of the matrix at the flanges D is shown at E.

I claim as new—

A journal shell-box constructed with two 5 matrices, A, deeper at the edges of the central rib than at the flanges D, and inclosed by side and end flanges, D B, and provided with a strengthening-rib, S, lying in the center of the shell between the matrices A and below

the flanges B, and the cavity of the shell filled to with soft anti-friction metal C, soldered in to come flush with the flanges D B, cover the rib S, and be inclosed wholly between the flanges, as specified, and for the purpose set forth.

FRANK R. CARGILL.
